(Cl. D40—1)

FIG. 1

FIG. 2

FIG. 3

FIG. 4

FIG. 1 is a left rear perspective view of a forage harvester embodying our new design.

FIG. 2 is a right rear perspective view thereof.

FIG. 3 is a right front perspective view thereof with a portion of the crop gathering unit removed to more clearly show the harvester.

FIG. 4 is a left front perspective view thereof.

The dominant features of our design reside in the portions of the drawings shown in full lines.

We claim:

The ornamental design for a forage harvester, substantially as shown and described.
